UNITED STATES PATENT OFFICE.

ISIDOR JOSEPH LEVY, OF NEW YORK, N. Y.

DESIGN FOR A HAND-BAG.

No. 40,084.

Specification for Design.

Patented June 22, 1909.

Application filed March 15, 1909. Serial No. 483,656. Term of patent 3½ years.

To all whom it may concern:

Be it known that I, ISIDOR JOSEPH LEVY, a citizen of the United States, and a resident of New York, in the county and State of New York, have invented a new, original, and ornamental Design for Hand-Bags, of which the following is a specification, reference being had to the accompanying drawing, forming a part hereof.

The figure is a view in elevation of a hand bag showing my design.

I claim—

The ornamental design for a hand bag as shown.

ISIDOR JOSEPH LEVY.

In the presence of—

LESTER F. DITTENHOEFER,
MICHEL KRAUS.
